ENGINE CLEANING AND CONDITIONING

John E. Vallerie, Norwalk, Conn.

Application March 13, 1942, Serial No. 434,538

18 Claims. (Cl. 134—21)

This invention relates to the cleaning and conditioning of engines, particularly internal combustion engines and associated parts, and especially to improvements in methods and apparatus for use in such cleaning and conditioning.

It is an object of the present invention to provide an improved method by which foreign material such as the products of oil and/or gasoline decomposition and sludge may be more effectively and economically removed from the internal component parts of an internal combustion engine than heretofore, without harmful effect on the several parts or on the engine as a whole, and to provide an apparatus for carrying out this improved method.

It is a further object of the invention to provide a method and apparatus for the foregoing purpose which will serve to clean various orifices, passages, oil lines, and other openings and to protect the same against being plugged or packed with foreign material at the time this material is being cleaned from other engine parts.

Another object of the invention is to provide an improved method and apparatus for cleaning foreign material from the jets, venturi, orifices, and other internal openings or passages in a gasoline carburetor.

Another object of the invention is to provide an improved method for effectively cleaning many related and associated parts of an internal combustion engine and to provide a particularly effective yet simple and easily transportable apparatus for carrying out this method, adapted for ready association and connection with standard parts of the engine and without dismantling the engine.

Features and advantages of the invention resulting from an attainment of the foregoing and other objects, include the provision of a method which takes advantage of the maximum clearances present in a cold engine to permit more effective and more complete action of a cleaning solvent, which makes possible an effective removal of foreign material loosened and dislodged by the solvent, which not only is effective in cleaning the combustion chamber and valves, but is also effective in cleaning and freeing piston rings, grooves and other parts of the engine, and which supplements the blow-out of the exhaust strokes of the pistons in voiding dislodged foreign material by the action of external suction applied to the regular pressure oil-distributing system of the engine, which suction action also tends to maintain the oil lines of the system and other passages free of accumulated foreign material.

which might be initially present therein or which might become lodged therein during the solvent treatment.

- A related feature of the invention resides in the injection of a cleaning solvent in vapor form and under outside pressure into the working space in the cylinders above the pistons, as through the intake manifold, of a cold engine while the latter is being turned over by an outside source of power.
- Another feature of the invention resides in the application of suction to the pressure oil-distributing system of the engine while injecting solvent in vapor form into the intake manifold as above set forth.
- Another feature of the invention resides in the solvent cleaning of oil pressure lines as well as other related parts of the engine, as a part of the entire method for the cleaning and conditioning of an engine.
- Another feature of the invention resides in the provision of a method which includes not only positive steps for effectively loosening and dislodging foreign material, but also for effectively voiding this material from the engine, particularly small openings, passages and grooves thereof where it would likely become packed or adversely caught and thus seriously and adversely affect the future efficiency, life and operation of the engine.
- Another feature of the invention resides in the provision of a method which includes not only steps by which the engine may be effectively cleaned, but also a step by which engine parts are conditioned and protected by the application of a plating oil.

- Another feature of the invention resides in the provision of an apparatus particularly adapted to be used in carrying on the entire method embodying the present invention as well as various related and component parts of that method.

Other objects, features and advantages will hereinafter appear.

- In the drawings:
- Figure 1 is a view showing in general outline the side of a conventional internal combustion engine and illustrating the apparatus of the present invention associated therewith in a manner for carrying out certain method steps of the present invention.

Fig. 10 is a detail view, partially in section, illustrating a special means associated with the vaporizing and dispensing unit of the apparatus.

Fig. 11 is an enlarged fragmentary sectional view taken substantially on the line 11—11 of Fig. 6.

Fig. 12 is a detail sectional view illustrating the association of the distributing hose of the apparatus with the vaporizing and distributing unit.

Before describing the present improvements and mode of operation thereof in detail it should be understood that the invention is not limited to the details of construction and arrangement of parts shown in the accompanying drawings, which are merely illustrative of the present preferred embodiments since the invention is capable of other embodiments, and the phraseology employed is for the purpose of description and not of limitation.

Referring more particularly to the drawings, there is shown in outline in Fig. 1 and diagrammatically in Fig. 2, for the purpose of illustrating the present invention, an internal combustion engine 20 of the well-known four-cycle type including, as is conventional, a cylinder 21 in which a reciprocable piston 22 is located and is connected through a connecting rod 23 to the crank shaft 24. In the normal operation of such an engine and, as is well understood, gasoline is drawn from a carburetor 25 through an intake manifold 26 and thence at the proper time through an intake valve 27 and into the engine cylinder above the piston where work is done on the piston prior to the exhausting of the products of combustion through an exhaust valve 28. As is usual the intake manifold may be provided with a suitable opening adapted to be connected with some part drawing on the vacuum of the engine and normally closed by a plug when the connection is not made.

As diagrammatically illustrated, the engine is of a usual type in which pressure lubrication is provided for many of the movably associated parts through a pressure oil-distributing system 29 including an oil gallery 30 from which oil lines lead to divers operating parts, such as an oil line 31 to the crank shaft 24, and other oil lines 32, 33, 34 and 35 to the cam shaft, filter, timing chain, and oil-pressure gauge, not shown, and to which an oil line 36 leads from a suitable oil pump 37 which draws oil from a crankcase 38.

Conventionally, oil directed to the crank shaft is conducted through suitable and usual passages to divers crank shaft bearings, and may also be conducted through other passages up through the connecting rods to the wrist pins. At the wrist pin, crankpin and other bearings to which

the passages lead small openings or channels normally are provided from which the oil escapes and eventually returns to the crankcase.

It is for operation on an engine of the pressure lubricated type that the method and apparatus of the present invention are particularly adapted, but this method and apparatus also may be advantageously used in connection with engines relying essentially on simple splash lubrication.

In the normal running of any internal combustion engine sludge is formed which, if not removed, has an adverse effect on the operation thereof. This adverse effect of sludge ranges from a slight loss of power to a point where the motor cannot operate at all, and from slightly more than normal oil and gasoline consumption to a point where such consumption is so great that further operation of the engine is economically untenable.

This sludge may be of the type comprising an emulsion of oil and water, which is a soft putty-like material resulting from condensation of water from the combustion products which escape the combustion chamber to the crankcase, or from a condensation of water vapor as it comes in contact with cold cylinder and crankcase walls, or from condensation of water from the air used for crankcase ventilation, or from any combination of these causes.

Also, this sludge may be of the type comprising oxidation products such as carbon, varnish, and tar which are formed through the tendency of petroleum products to decompose or crack when exposed to high temperature, and also to impurities, such as road dust, which enter the motor through inefficient intake air filtration and form deposits with the above-mentioned products.

It is and has been recognized that an internal combustion engine in its normal operation, under conditions other than those which are very carefully controlled in a laboratory, will become subject to both types of sludge. Emulsion sludge is peculiar to too low a temperature and oxidation sludge to too high a temperature. Variations in weather, load and speed as well as the necessity for starting and stopping the engine result in both types of deposits in any engine, and no amount of variable temperature control completely eliminates these formations. The very heat necessarily resultant from the cylinder combustion presupposes petroleum by-products and all of these are not exhausted. Also, the products of combustion from a gallon of fuel contain approximately one and one-eighth gallons of water, some of which will eventually mix with the lubricating oil.

"Blow-by," which is a term describing the by-products of combustion which leak past the piston rings, is found in any engine. Combustion pressures of a gasoline engine reach as much as 450 pounds per square inch, so that even in a new engine 1% to 3% of the total air taken through the carburetor escapes past the piston rings.

In a badly sludged motor, the greater part of the crankcase surfaces are covered with putty-like sludge deposits, the oil pump strainer is usually clogged with the same material, and often the oil pressure lines are partially closed. In addition, the valve mechanism which projects into the valve chamber is completely covered with this emulsion and a layer of the same is on the valve covers. Thick deposits of oxidation sludge in the shape of carbon will be found on the cylinder

heads, the piston heads, around the valve seats, and about the lip of the cylinders. If the pistons are removed, the piston rings will frequently be found tightly stuck in the grooves. This is particularly common to the top compression ring. The grooves themselves will be coated on all sides with a tarry substance, as will also the rings. If the oil ring is of the slotted type, these slots will frequently be found nearly filled with sludge. In addition, the walls of the piston and cylinder walls and the sides of the connecting rods are badly discolored with a hard, brittle material known as "engine varnish."

If sludge impedes the seating of either exhaust or intake valves, the engine will not run well and very frequently results in valve burning. If fresh oil is added to an already oxidized oil in the crankcase, certain resins which are soluble in the oxidized oil will frequently curdle and form "coffee grounds" which are of a large enough size to plug the oil passages.

The most readily apparent adverse effect of sludge, however, and that which causes the earliest detriment to power and economy, is the impedance of proper piston ring action. The most common reaction in the rings is for sludge in the top compression ring groove to seal the ring tightly in the groove, thus impeding its natural expansion and allowing blow-by from the compression chamber to the next ring, which is frequently an oil wiper ring. The great heat on the oil causes additional oxidation, sticking of the wiper ring, and so on down until the oil control ring slots and oil return orifices are completely clogged both by the oxidation sludge and the emulsion sludge thrown up in the oil from the crankpin. With insufficient lubrication there is greater wear on the cylinder walls, resulting in larger and larger clearances for blow-by and a resultant increase in emulsion sludge caused by combustion chamber blow-by condensation. If too much oil reaches the cylinder walls it is immediately burned—in some cases is practically pumped past the rings for burning. With the compression loss much power is sacrificed and fuel economy rapidly diminishes. The cycle is a vicious one.

Recognizing the desirability of removing sludge and other foreign material from motors, many prior proposals have been advanced. For example, it has been proposed to completely take-down and clean a motor. However, such a procedure entails such a considerable amount of time with attendant loss of productive use of the motor that it is very costly not only from the standpoint of labor involved, but also from the standpoint of the motor being held idle. The importance of these cost factors are readily apparent when it is borne in mind that these adverse conditions sometimes become acute within the first five thousand miles of motor vehicle operation, especially in the case of trucks engaged in severe service.

Frequent oil changes help, but are expensive and do not prevent and only delay the creations of the adverse conditions mentioned. Also, crankcase flushing will serve to remove crankcase sludge and in some cases be of some help in cleaning oil lines. Additionally, the sucking-in to the intake manifold of certain carbon solvents while the engine is running hot under its own power is of assistance in loosening sludge formed on valves, in the combustion chamber and on the tops of the pistons. None of these prior practices apart from the complete taking-down of the

motor, however, are wholly effective and none of them provide treatment to effectively prevent piston ring blow-by or to safeguard the divers oil lines and passages against becoming clogged during the cleaning treatment.

With the present invention a very effective engine cleaning treatment is provided, overcoming shortcomings of prior proposals and serving not only to effectively loosen and dislodge foreign material, but also to effectively void this loosened and dislodged material while at the same time safeguarding the oil lines and oil orifices against clogging either during or subsequent to the cleaning.

10 The present invention, similarly to certain prior proposals utilizes a cleaning solvent which is introduced into the intake manifold of engine. However, it differs from any prior proposals of which the present inventor has knowledge not only in the manner in which the cleaning material is introduced, but also in important conditions maintained during the introduction of the cleaning material, and in other important ways which will hereinafter be 15 pointed out in detail.

20 The method embodying the present invention, to obtain the optimum and desired results, is performed on a cold motor as distinguished from a hot motor. Because of this important fact relatively substantial clearances are insured for the passage of cleaning solvent and of foreign material being voided. For example, it is common practice to allow .00075" 25 clearance per inch of piston diameter for grey iron piston skirts. A 4" piston on this scale would require .003" clearance. Many authorities recommend a clearance of .001" per inch of piston diameter on pistons of motors subject to abusive treatment. Thus a 4" piston in a 30 truck motor would have a piston skirt clearance of .004", with an additional .001" added if the motor is constantly subjected to high speeds. Upper piston lands are allowed additional clearance. It is customary to allow .0035" per inch for the top land, .003" per inch for the second land, and .002" per inch of diameter for the third land. Clearances such as the above are negligible when a motor is but moderately heated, and much of the effectiveness of this invention is spent if heat is present.

35 In carrying out the present invention and starting with a cold motor, the crankcase of which has been drained of oil, a suitable cleaning solvent is used which preferably should be 40 of a type not harmful to any combination of metals employed in motor manufacture, that is effective without heating, is readily vaporized or atomized, and is noncombustible. An example 45 of a solvent which has been found suitable is a product of Chemical Supply & Service Co. of Westwood, New Jersey, named "Solvit."

50 Advantageously and importantly this cleaning material is injected under the influence of outside pressure and in vapor form into the working space above the pistons, as through the intake manifold, of the subject engine while the latter is being turned over in a cold condition by an outside source of power. The self-starter, with which all usual internal combustion engines now in general use are provided, offers such a convenient source of outside power. However, it will be appreciated that other sources of outside power may be utilized. It is 55 important that if the self-starter is used as the

outside power source, the ignition not be turned on.

Simultaneously with the injection of the cleaning vapor, suction is applied to the pressure oil-distributing system 29, as by a suitable connection to the oil gallery 30, either directly through a fitting placed in an opening therein or indirectly as through a connection with the usual oil pressure gauge line 35, to subject the oil gallery and all oil lines and passages communicating therewith to the suction or vacuum action and to complement the pressure in the engine cylinder, or cylinders, in obtaining maximum cleaning action by the vaporized solvent.

Advantageously, prior to turning over the cold motor and immediately prior to injecting the vaporized cleaning material, air under pressure is forced into the intake manifold to build up an initial pressure therein. While preferred, however, this initial step of applying pressure to the intake manifold is not essential to a satisfactory operation of the method.

As the cold motor is turned over, with the vaporized cleaning material under pressure being injected into the intake manifold, the intake valve of each cylinder opens in proper sequence, permitting the vaporized solvent to pass into the cylinder. In this passage of the solvent into the cylinder the pushing action of the outside pressure source is complemented by the natural suction created in the cylinder by the movement of the piston through its intake stroke. At the same time, vaporized solvent also is forced by the valve guides and stems to clean the members of the valve assemblies.

When the intake valve of a particular cylinder closes and the piston moves in the compression stroke of its cycle, the solvent material is compressed and forced by this action of the motor the length of the cylinder. During this compression of the solvent vapor in the cylinder, a certain amount is forced into the structure of oxidation deposits on the piston and cylinder heads. Moreover, since the subject motor is cold, it has been possible to take advantage of the normal clearances allowed for the heat expansion of engine parts. Hence, some of the solvent and the material loosened thereby is forced past the piston rings. Also there may be relative vertical movement between the piston and the rings, forcing the solvent into the deposits of foreign material in the ring grooves and onto the surfaces of these grooves.

As the piston moves in what under normal operating conditions of the engine would be its power stroke, both the intake and exhaust valves remain closed, and some of the solvent material which has been forced along the cylinder walls during the compression stroke will be sucked back around the piston and into the compression chamber by the reverse suction created by the enlargement of the volume ahead of the piston as the latter moves in the power stroke. This further aids the ring and ring groove cleaning.

During the exhaust stroke a considerable amount of the cleaning solvent and dislodged foreign material is voided through the exhaust valve port and the exhaust manifold. Also, during the compression stroke, in particular, much of the foreign material and solvent is carried into the crankcase by passing the piston and piston rings. This latter result will be readily apparent when it is borne in mind that in a 4-

inch bore motor, for example, there will be an allowance of approximately .021 inch at each piston ring gap, which further permits the solvent to progress the full length of the cylinder.

5 In addition, due to the rapid oscillation of the pistons as the engine is turned over in a cold condition by the outside source of power, and to the loosening or softening of the foreign material on the rings and in the ring grooves, the rings 10 are loosened in the grooves enabling the solvent to gain access to further clean the rings, grooves and oil slots and passages associated therewith.

Moreover, as solvent vapor passes the piston and piston rings some will be sucked into usual 15 oil passages which, as before explained, are in communication with the pressure oil-distributing system, and hence are subjected to the drawing action of the outside source of suction. This suction thus aids in obtaining a maximum clean- 20 in action from the solvent and, of special importance, acts to draw off foreign material loosened thereby and acts to safeguard the oil passages and particularly the many tiny openings 25 free or substantially free of foreign material dislodged from other engine parts, as for example the piston rings and ring grooves, during the forced vaporized solvent cleaning action to which they are being subjected.

30 Following the foregoing steps of simultaneously injecting solvent vapor into the intake manifold while applying suction to the pressure oil-distributing system, the turning-over of the motor may be discontinued and an increased

35 suction applied to the pressure oil-distributing system for a short time. In tests made, an application of this increased suction for about a half minute has proved to produce satisfactory results. This effectively drains the oil lines and 40 passages and serves to pick up any hard sludge deposits which may have entered therein as a result of the solvent action and which might not have been removed during the suction action applied during the forced injection of the solvent 45 through the intake manifold. Also, sludge deposits in small reservoirs connected to the oil lines are drained and cleaned out in this manner.

The steps of solvent injection and then increased application of suction, described above, 50 may be and preferably are repeated several times.

Concurrently with the forcing of vapor solvent into the intake manifold to clean the respective engine cylinders and associated parts as explained above, it is contemplated that the 55 passages of the carburetor, which carburetor constitutes a combustible charge preparing and feeding means, be cleaned of foreign material which might otherwise impede the satisfactory operation of this important part of the motor.

60 Thus, the throttle valve may be opened for a part of the time, allowing a portion of the vapor solvent to be forced through carburetor passages in a direction opposed to the usual flow of gasoline and air. Also, carburetor leaks, as by gaskets, may be detected, particularly if the usual 65 butterfly choke valve is closed for a portion of the time that the solvent is being forced into the carburetor, and action taken to eliminate these leaks.

70 After the performance of the foregoing steps, vapor solvent under pressure is injected into the pressure oil-distributing system, as, for example, at the same place where suction was applied before. During this solvent injection step, as during 75 the step of injecting solvent into the intake

manifold, the motor is turned over in a cold condition by an outside power source. If the motor is of the type in which full pressure lubrication is provided to the wrist pin, some of the solvent vapor will be forced to that point and sprayed out to act on the engine parts, in that area. Other portions of the solvent will spray and seep out of openings in the oil passages leading up to the wrist pin and, together with the spray from the wrist pin area, create a penetrating solvent vapor fog. If the motor is of the type in which full pressure lubrication is provided only to the crankpin, the general result is much the same, and in both cases the passages and oil lines of the pressure oil-distributing system, and the bearing surfaces, are effectively cleaned by solvent vapor.

Upon completion of the solvent cleaning steps above described, it has been found advantageous to apply suction to the top of the respective engine cylinders, as through the usually tapped holes for the spark plugs, while the piston in the cylinder to which suction is being applied is stopped during its compression stroke. In carrying out the foregoing operation the engine is turned over, as by a hand crank, to bring a given piston to a position in its compression stroke, the turning over is discontinued and the suction applied. A like operation is carried out in connection with each of the cylinders. The suction thus applied serves to lift the piston rings and thus permit the various ring expanders, which frequently become improperly seated due to sludge, grit and other foreign material prior to the solvent cleaning steps, to reseat themselves properly.

Next, air under pressure is blown into the intake manifold while the engine is being turned over slowly, again by means of an outside source of power. A hand crank has been found satisfactory for this purpose. The air blast serves as an air wash to remove all but a negligible amount of solvent from the cylinders and forces remaining foreign material to the crankcase. Some material and air will, of course, be voided through the exhaust.

Following the air wash described above, a suitable plating oil in vaporized form is blown in the intake manifold while the engine is being turned over by an outside source of power, and at the same time a connection is made to the pressure oil-distributing system and an outside source of suction applied thereto. Vaporized plating oil then is blown into the pressure oil-distributing system while the motor is being turned over by an outside power source. These two oil plating operations together, which are seen to be similar to the solvent vapor operations, serve very effectively to lubricate friction surfaces by placing a film of oil thereon. The plating oil, it will be appreciated, should be of such a character that it is susceptible of being vaporized or atomized and thus provide an oil vapor fog which sticks to the surfaces that have been blown dry or substantially dry by the air blast above described.

When the oil plating operations have been completed, the drain plug is replaced in the crankcase and the latter thoroughly flushed. In connection with the crankcase flushing step it has been found particularly advantageous to pour a suitable crankcase flushing material into the crankcase up to the recommended oil level and then agitate the flushing material in the crankcase by blowing air out through perforations ad-

70 jacent the end of a tube 39, see Fig. 9, inserted through the usual dip stick opening to the crankcase.

In tests made, an agitation of the flushing material for about five minutes has produced good results in the loosening of the sludge initially in the crankcase and in further dissolving the sludge deposits forced from the cylinders during the previous solvent treatment.

10 The crankcase is then drained of the flushing material and accumulated sludge, preferably while the agitation by air is continued, leaving the crankcase and oil strainer clean. The crankcase is then refilled with any suitable lubricating oil.

15 With the completion of the foregoing step, the motor is ready for use.

Intimately related to the method above described for cleaning and conditioning internal combustion engines, is an apparatus 40 particularly constructed and adapted to be associated with an internal combustion engine for the carrying out of the entire method up to the filling of the crankcase with fresh lubrication oil. The general organization of the apparatus, and the manner of its association with an internal combustion engine to carry out the steps of simultaneously forcing a solvent in vaporized or atomized form into the intake manifold 26 while applying a suction to the pressure oil-distributing system is shown in Figs. 1 and 2.

20 As there illustrated the apparatus 40 includes a compressor unit 41 having a pressure head 42 and a suction or vacuum head 43, respectively connected to a vaporizing and dispensing unit 44, as by a hose 45, and to a suction or vacuum trap unit 46, as by a hose 47. Advantageously, a distributing hose 48 is connected to the vaporizing and dispensing unit at one end and is provided with a suitable fitting 49 at the other end, see Fig. 8, adapted to be associated with the engine part to which the pressure head 42 of the compressor unit is to be connected. A suction hose 50, similar to the distributing hose 48, is connected at one end to the trap unit 46 and at the other end is provided with suitable fitting, for example similar to the fitting 49, adapted to be screwed into or otherwise associated with the engine part to which the suction head of the 25 compressor unit is to be connected.

25 The compressor unit 41, as illustrated, is in general construction similar to units now readily available on the market for use in connection with apparatus for spraying paint and other material, and includes a cylinder 51 in which a piston, not shown, is reciprocated through usual and well-known connections with a drive shaft 52 rotatable as by an electric motor 53. Also, as is usual a cap 54 is suitably secured to the top of the cylinder, having a bottom wall 55 with an intake opening 56 and an outlet opening 57 therein, which openings are respectively controlled by conventional and suitable spring pressed valves respectively adapted to permit air being drawn into and forced out of the cylinder as the piston moves down and then up therein. As is likewise conventional, the outlet opening 57 is connected in the well-known manner through a connecting pipe 58 to a pressure chamber constituted by the pressure head 42 of the compressor unit. A suitable fitting 59 is provided in the pressure head for connection to the hose 45 leading to the vaporizing or atomizing unit 44 which, as shown, may be of the same construction as units now in general use in ap-

paratus for spraying paint and other material. A pressure release or safety valve 60 of any well-known and suitable construction also preferably is connected to the pressure head.

Of importance, however, the cap 54 of the cylinder, which has an upwardly extending side wall formation 61 to provide a chamber 62 above the bottom wall 55 and in communication with the intake opening 56, is provided with a closure disk 63 adapted to be held tightly down on the top of the side wall formation by a suitable bolt 64 and thus effectively close the chamber 62 to form with the bottom wall 55 and side wall formation 61, the suction head 43 of the compressor unit. Advantageously a gasket may be provided to most effectively seal the closure disk 63 relative to the cap.

Also of importance, there is fitted into a suitable opening in the closure disk 63, a fitting 66, similar to the fitting associated with the pressure head, for connecting the hose 47 to the trap unit 46. And, advantageously, a suction control valve unit 67 is fitted in the closure disk to, like the fitting 66, communicate with the chamber 62 of the suction head. The control valve unit may be of the well-known type in which an apertured cross plug may be turned by a usual turning head 68 to close, partially close, or open the valve passage.

The vaporizing and dispensing unit 44, as illustrated most clearly in Figs. 4 and 5, and as indicated above, may be of the type conventionally used in spraying paint or other material. It includes a container 69, which may be of metal, on the top of which is screwed a cap 70 carrying the control and vaporizing elements of the unit.

Thus, as shown, the cap is formed with a superposed body 71 of integral construction including an upstanding central cylindrical portion 72 topped by a horizontally disposed cylindrical portion 73 from which at right angles extends a second horizontally disposed portion 74 adapted to be connected through a suitable fitting with the hose 45 from the pressure head 42 of the compressor unit. Providing communication from the interior of the portion 74 to the top of the central cylindrical portion is a passage 75 in the body. Extending down into the container to a point adjacent the bottom thereof from a passage 76 in the body communicating with a bore 77 in the portion 73 is a tube 78. Thus as pressure is built up in the container by air forced therein through the passage 75, material in the container is forced up through the tube 78 and into the bore 77 from which it is expelled through a nozzle 79 fitted into the delivery end of the bore.

As is usual a needle valve 80 conveniently manipulatable, as by a trigger 81, is provided for controlling the discharge of material through the nozzle. Atomization or vaporization of the material discharged through the nozzle is effected by air directed through a second passage 82 communicating with the interior of the second portion 74 and extending to a point adjacent the nozzle 79 where a restricting cap 83 fitted to the end of the hose 48, see Fig. 12, and held firmly against the face of an attaching flange 84 on the forward end of the body portion 73 by a suitable attaching collar 85, serves to intimately associate the air and discharged liquid material and thus break up and vaporize or atomize the latter before it enters the hose 48.

The effectiveness of the vapor fog has been

found to be enhanced and the operation of apparatus improved if an enlarged chamber is interposed between the point of initial vaporization and the hose. As shown in Fig. 10 such a chamber 86 is provided by a horizontally disposed cylindrical canlike member 87 having a centrally disposed connecting portion 88 at the inlet end adapted to be screwed or otherwise secured to the attaching flange 84 on the vaporizing unit and having a restricting section 82 which functions like the restricting cap 83 above described to effect an intimate association of air under pressure and the liquid discharged from the nozzle. At the outlet end thereof, the canlike member is provided with another centrally disposed connecting portion 90 adapted through a suitable fitting 91 to be connected to the hose 48.

The suction trap unit 46, as shown most clearly in Figs. 6, 7, and 11, is in general construction similar to that of the vaporizing and dispensing unit 44 above described, including as that unit a container 92 on the top of which is a cap 93 having superposed thereon a body 94 of integral construction made up of an upstanding central cylindrical portion 95 topped by horizontally disposed portions 96 and 97 at right angles to each other and with a passage 98 extending from the interior of portion 97 to the top of the cylindrical portion 95. Also similarly to the vaporizing unit, a tube 99 is provided which extends downwardly in the central cylindrical portion from a passage 100 communicating with a bore 101 extending to a flanged attaching end 102 on the horizontal portion 96. Importantly, however, it is to be noted that in the trap unit, while the free open end of the tube 99 is located downwardly an appreciable distance from the top of the upstanding cylindrical portion and hence is spaced downwardly from the terminus of the passage 98, it is located adjacent the top and not the bottom of the container. Also, importantly it is to be noted that no passage is provided from the flanged end 102 of the portion 96 to the interior of the portion 97 and no nozzle corresponding to the nozzle 79 is fitted into the end of the bore 101. The needle valve control trigger, present in the vaporizing unit 44, is likewise omitted, and the bore 101 at the end remote from the flanged attaching end 102 is closed as by a plug 103.

In associating the suction trap unit 46 with the compressor unit, the hose 47 from the compressor unit is connected to the portion 97 in the same manner as the hose 45 from the pressure head 42 is connected to the portion 74 of the vaporizing unit. Likewise, and as shown, the hose 50, adapted to be connected to that part of the engine to which suction is to be applied, may be connected to the flanged end 102 of the portion 96 in the same manner as the delivery hose 48 is connected to the attaching flange 84 of the vaporizing unit.

When the apparatus above described is associated with a motor, as shown in Figs. 1 and 2, with the hose 48 attached by a suitable fitting to and in communication with the intake manifold and with the hose 50 attached by a suitable fitting to and in communication with the oil gallery, the method steps of initially building up pressure and then simultaneously forcing solvent in vaporized form into the intake manifold and applying suction to the pressure oil-distributing system, may readily be carried out. Thus, by starting the compressor, and with the

needle valve 80 in nozzle closing position, air under pressure is forced through the hose 45, passage 82 and hose 48 into the intake manifold.

Then by merely pulling the trigger 81 the discharge nozzle 79 is opened and the solvent, which has been placed in the container, is forced out into the hose 48 in vaporized form and thence into the intake manifold. Simultaneously the suction head of the compressor unit draws through the hose 47 and through the passage 98 to build up a partial vacuum in the container of the suction trap and hence there is created a draw or suction at the oil gallery through the tube 99, passage 100 and hose 50. Solvent, foreign material and trapped oil in the pressure oil-distributing system is thus drawn through the hose 50 and directed down to the bottom of the container 92 by the tube 99. However, and of importance, because the free end of the tube 99 is spaced downwardly from the terminus of the suction passage 98 in the body structure of the cap 93 and directs the removed material to the bottom of the container, this removed material is trapped in the container and is not adversely sucked back to the compressor unit. Also, because the free or expelling end of the tube 99 is adjacent the top of the container, a substantial amount of material may be trapped without adversely closing the expelling end of the tube.

To carry out the step of forcing vaporized solvent into the pressure oil-distributing system it merely is necessary to disconnect the hose 50 from the oil gallery, connect the hose 48 thereto instead, and then operate the trigger 81 in the same manner as when injecting solvent into the intake manifold.

The step involving the application of suction to the top of the cylinders as through a connection to the respective tapped holes for the spark plugs is accomplished through attaching, as by a suitable fitting, the suction hose 50 to each of the spark plug holes in turn and operating the compressor unit. It is not necessary to disassociate the pressure hose 48 from the oil gallery during the immediately foregoing operations.

Control of the suction during the foregoing operations may be readily achieved by regulating the control valve 67 on the suction head 43 of the compressor. Thus during the operation of applying suction to the pressure oil-distributing system during the forced injection of vaporized solvent into the intake manifold, it has been found that best results are obtained by regulating the same to a fully open position. For the step of applying increased suction to the pressure oil-distributing system following the injection of solvent into the intake manifold very good results have been obtained by regulating the control valve to a fully closed position. For the step of applying suction to the top of the cylinders, as by a connection to the respective tapped spark plug receiving holes, good results also have been obtained by regulating the control valve to a fully closed position.

The association of the apparatus with the engine for carrying out the air wash step may be the same as for the initial step of building up an initial air pressure in the intake manifold. And, the association of the apparatus with the engine and the operation of the apparatus for the oil plating steps are the same as for the solvent injection steps, it being understood, of course, that a suitable plating oil is placed in the container 69 instead of a cleaning solvent.

Of importance, it is to be noted that the crankcase is drained prior to the beginning of

the solvent cleaning steps and that the drain plug is not replaced until after the solvent cleaning and oil plating steps have been completed. This serves to prevent an adverse accumulation of oil and/or the products of the cleaning steps in the crankcase where this material might be picked up by the usual oil pump 31 and adversely circulated in the pressure oil-distributing system.

10 In the crankcase cleaning and flushing operation, air under pressure for agitating the flushing material may be obtained for the tube 39 by connecting the latter by some suitable and convenient means to the end of the hose 48 and then operating the compressor.

15 It is thus seen that the apparatus provided by the present invention is such that it is particularly adapted to be readily associated with the engine in carrying out the several steps of the method.

20 Moreover, it will be readily appreciated that while the method and apparatus of the present invention has been described for illustrative purposes in connection with an engine of the four-cycle type, the invention is likewise applicable to engines of the two-cycle type and other types, and to engines involving means other than a conventional carburetor for preparing and feeding the combustible charge, for example to engines of the Diesel type.

25 Variations and modifications may be made within the scope of this invention and portions of the improvements may be used without others.

30 Having thus described the invention, what is claimed as new is:

35 1. A process for cleaning deposits of foreign material from an internal combustion engine, including the steps of turning over the engine 40 while cold through a cycle of operations by the utilization of an outside source of power; simultaneously injecting a cleaning material in vapor form into the intake manifold of said engine; and simultaneously applying suction to the pressure oil-distributing system of said engine 45 through a connection with an outside source of suction.

40 2. A process for cleaning deposits of foreign material from an internal combustion engine 50 without dismantling the engine, including the steps of turning over the engine by the utilization of an outside source of power to cause movement of the pistons and related mechanisms through a cycle of operations; and simultaneously introducing a cleaning material in vapor form under the influence of outside pressure into the engine through the intake manifold of said engine.

45 3. A process for cleaning deposits of foreign material from an internal combustion engine 55 without dismantling the engine, including the steps of turning over the engine through a cycle of operations by the utilization of an outside source of power; simultaneously introducing a cleaning material under the influence of outside pressure into at least one cylinder in said engine; and simultaneously applying suction to the pressure oil-distributing system of said engine to draw the pressure-introduced cleaning material through the cylinder.

60 4. A process for cleaning deposits of foreign material from an internal combustion engine 65 without dismantling the engine, including the steps of turning over the engine through a cycle of operations by the utilization of an outside

source of power; simultaneously injecting a cleaning solvent into the intake manifold of said engine; and subsequently injecting air under pressure into said intake manifold while turning the motor over through the utilization of an outside source of power.

5. A process for cleaning deposits of foreign material from an internal combustion engine and associated mechanisms without dismantling the engine, including the steps of turning over the engine through a cycle of operations by an outside power source; simultaneously injecting a cleaning solvent in vapor form into the intake manifold of said engine; and opening the throttle valve while injecting said cleaning solvent to permit the solvent to enter the carburetor passages.

6. A process for use in connection with the cleaning elements of an internal combustion engine without dismantling the same, including the steps of injecting under pressure into the intake manifold of the engine a cleaning solvent in vapor form; and opening the throttle valve to release the solvent under pressure into the carburetor passages.

7. A process for cleaning deposits of foreign material from an internal combustion engine without dismantling the engine, including the steps of turning over the engine while cold through a cycle of operations by an outside power source; and simultaneously injecting under pressure into the intake manifold of said engine a cleaning solvent in vapor form.

8. A process according to claim 7, including the step of injecting air under pressure into the intake manifold after the injection of the cleaning solvent and while the engine is being turned over slowly by an outside power source.

9. A process according to claim 7, including the subsequent step of applying suction to the working space of an engine cylinder on the working side of the piston therein while movement of the latter is stopped.

10. In combination with an internal combustion engine having a pressure oil-distributing system and an intake manifold, means for vaporizing a cleaning solvent and expelling the same under pressure; conduit means connecting said vaporizing and expelling means to said intake manifold; suction creating means; and conduit means connecting said suction creating means to said pressure oil-distributing system.

11. In combination with an internal combustion engine having a pressure oil-distributing system and an intake manifold, means for vaporizing a cleaning solvent and expelling the same; conduit means connecting said vaporizing and expelling means to said intake manifold; suction creating means for drawing material from said pressure oil-distributing system; conduit means connecting said suction creating means to said pressure oil-distributing system; and a trap associated with said last-named conduit means intermediate said pressure oil-distributing system and said suction creating means, for collecting material drawn from said pressure oil-distributing system.

12. In combination with an internal combustion engine having a pressure oil-distributing system and an intake manifold, a compressor unit having a pressure and a suction side; dispensing means including a container for a motor cleaning solvent, connected to said pressure side and having a solvent vaporizing and discharging means; conduit means connecting said discharg-

ing means and said intake manifold; and a trap for collecting material from said pressure oil-distributing system, connected to and intermediate the latter and the suction side of said compressor unit, said trap including a closed container having spaced openings respectively communicable with said suction side and said pressure oil-distributing system, said suction side opening being located above the other opening.

13. An apparatus for use in cleaning and conditioning an internal combustion engine unit, including a compressor unit having a suction head and a pressure head; a vaporizing and dispensing unit having a discharge head and having a control means for said discharge head; conduit means operatively connecting said pressure head to said vaporizing and dispensing unit; conduit means having an end operatively associated with said discharge head and an end for operative association with a part of said engine unit; a suction trap unit including a closed container and having a pair of passages communicable with the interior of said container; conduit means connected at one end to said suction head and 25 at the other end to said suction trap to communicate with the interior of said container through one of said passages; and means connected to said suction trap to communicate with the interior of said container through the other 30 of said passages, for operative association with a part of said engine unit.

14. An apparatus according to claim 13 in which the conduit means associated with said discharge head includes a means having an enlarged chamber with an inlet associated with said discharge head and with an outlet for association with that part of the engine unit to which pressure and vapor are to be applied.

15. A process for reconditioning an engine having at least one cylinder with a piston therein and having a pressure oil-distributing system, including the steps of: turning the engine over by an outside power source while the engine is in a cold condition and the crankcase is drained of oil, and simultaneously with the turning over of the engine forcing a solvent in vapor form into the working space of at least one engine cylinder on the working side of the piston therein and suction drawing through oil passages of the pressure oil-distributing system associated with operating parts of the engine in a direction opposed to the usual forced passage of oil therein.

16. A process according to claim 15, including the subsequent step of applying suction to the working space of the engine cylinder on the working side of the piston therein while movement of the latter is stopped.

17. The process of cleaning the top cylinders of an internal combustion engine without dismantling the engine including the steps of turning said engine over by the utilization of an outside source of power to cause movement of the piston and related elements through a cycle of operations; simultaneously injecting a cleaning material in vapor form under the influence of outside pressure into the top of the cylinders to clean the deposits of foreign material therein, the cleaning material being forced and drawn along the pistons and around the rings to clean foreign material therefrom; and applying a suction to the top of the cylinders of the engine to withdraw the excess vapor therefrom and to draw the rings back to proper position.

18. A process for cleaning deposits of foreign material from an internal combustion engine

having at least one oil line therein without dismantling the engine, including the steps of applying air pressure to said intake manifold to build up an initial pressure therein; applying a suction to the oil line prior to the turning over of the engine and the injection of the cleaning solvent into the intake manifold; turning over the engine by the utilization of an outside source

of power to cause movement of the pistons and related mechanisms through a cycle of operations; and simultaneously with the turning over of the engine introducing a cleaning material in vapor form under the influence of outside pressure into the engine through the intake manifold of said engine.

JOHN E. VALLERIE.
